[57] CLAIM

The ornamental design for a combined air compressor and flashlight, as shown.

DESCRIPTION

FIG. 1 is a front, top and right side perspective view of a combined air compressor and flashlight showing our new design;

FIG. 2 is a top plan view thereof;

FIG. 3 is a front elevational view thereof;

FIG. 4 is a right side view thereof;

FIG. 5 is a left side view thereof;

FIG. 6 is a rear elevational view thereof;

FIG. 7 is a bottom plan view thereof; and

FIG. 8 is an exploded perspective view thereof, with the flashlight portion shown rotated ninety degrees.

The broken-line showing of the numerals on the panel and the tubular element are for illustrative purposes only and form no part of the claimed design.
